BINDING STRIP FOR SPRING MATTRESS
STRUCTURESJohn G. Platt, Carthage, Mo., assignor to Flex-O-
Lators, Inc., Carthage, Mo., a corporation of
Missouri

Application January 27, 1951, Serial No. 208,108

5 Claims. (Cl. 5—360)

1

This invention relates to new and useful improvements in spring mattress construction, and relates particularly to binding strips for the marginal edges of the coil spring of such mattresses. It is an improvement over the structure shown in my copending application Serial No. 163,345, filed May 22, 1950.

An important object of the present invention is the provision of a cushioned binding strip for the marginal edges of spring mattress structures so constructed that when it is applied to the mattress the cushioning material is disposed nearly entirely on the outer faces of the mattress and within the marginal limits thereof. This provides a more complete and efficient utilization of the cushioning material, and for protection and reinforcement of the binding strip itself by the mattress springs.

Another important object is the provision of a binding strip of the class described which provides a padding support surface extending inwardly from the edges of the mattress a considerable distance.

Other objects are the provision of a binding strip which is simple, economical, easily manufactured and applied, strong in tension while quite flexible, and adaptable for use in a wide variety of spring assemblies.

With these objects in view, as well as other objects which will appear in the course of the specification, reference will be had to the drawing, wherein:

Fig. 1 is a fragmentary plan view of a spring mattress assembly, with binding strips embodying the present invention applied thereto.

Fig. 2 is an enlarged fragmentary section taken on line II—II of Fig. 1.

Fig. 3 is a transverse section of the binding strip, shown laid out flat before application to the spring mattress.

Fig. 4 is an inner face view of a section of the binding strip, broken away to show the various layers thereof.

Like reference numerals apply to similar parts throughout the several views, and the numeral 2 applies to a spring mattress comprising as assembly of a plurality of spool-shaped helical springs 4 arranged in parallel spaced apart rows with their axes substantially parallel. Each of said springs has a substantially circular top loop 6 and bottom loop 8, said top and bottom loops lying respectively in planes forming the upper and lower faces of the assembly. The top loops of adjacent springs in each row of springs overlap slightly, and are joined by a plurality of helical binder coils 10 which extend across the upper face of the assembly transversely to the

2

rows of springs, and which extend between corresponding pairs of springs in each row of springs, coiling about the overlapping portions of the top coils 6 thereof. Binder coils 10 similarly join the bottom loops 8 of the springs, as indicated in Fig. 2. It is to be understood however, that the arrangement of springs 4, and the means for joining them, are of no importance in the present invention, which relates only to the binding of the marginal edges of the spring assembly.

The binding strip, as shown in the drawings, includes a cover or body member 14 made of an elongated strip of pliable material such as paper, cloth, or the like, crepe paper being preferable since it has desirable characteristics to be described later. Said strip is folded longitudinally at 18 to produce an inner layer 16 and an outer layer 20. Fold 18 is not in the midline of member 14, but is offset therefrom whereby outer layer 20 is wider than inner layer 16, and projects outwardly from the edge 22 of said inner layer to form a flap 24. Between said inner and outer layers, and coextensive with the inner layer, is a double thickness 26 of a yieldable material such as a thick but soft paper having depressions formed therein commonly known as "waffled" or "dimpled" paper. It is to be understood however, that other materials adapted to import a cushioning effect and a degree of stiffness to the binding strip could be used. Inner layer 16 is more than half as wide as the entire binding strip, as shown in Figs. 3 and 4.

The binding strip is held in assembly by a line of stitching 28 extending longitudinally of the strip substantially in the midline thereof, and a parallel line of stitching 30 spaced apart from line 28 in the direction of the folded edge 18 of the strip. Both of said lines of stitches extend through inner layer 16, the double thickness of waffle paper 26, and outer layer 20. Between said lines of stitching, outer layer 20 is offset outwardly to form a loop 32 for containing a cord 34 of a cushioning material. As shown, the cord comprises twisted strands of tissue paper, although it is to be understood that other suitable materials such as cotton, sisal, jute, wood pulp, or the like, could be used. Said cord has a core wire 36 extending therethrough. Said wire is small enough to possess a high degree of flexibility, yet imports a high tensile strength to the binding strip. The entire inner surface of the binding strip, comprising the outer face of layer 16 and the inner face of flap 24, has applied thereto a layer of adhesive 38. Said adhesive is preferably pressure sensitive, and of a type that will adhere only to itself, such as latex.

In use, the binding strip is folded longitu-

dinarily along stitch line 28, and disposed, for example, about the upper marginal edge of the spring assembly 2, with the outer portions of the top loops 6 of the marginal springs 4 extending into the fold thereof, as shown in Fig. 2. Flap 24 is then pressed firmly against layer 16, until the adhesive on these parts is firmly joined. The waffle paper layers 26 are flattened by the folding action where they wrap about the spring loops 6.

This structure is considered to have several advantages over any known previous binders, and over that shown in my own copending application. The primary purposes of the binding strip are of course to protect the upholstery layers which are commonly applied over the spring assembly against wear by the friction of the springs thereagainst, and to provide greater comfort for the user. A problem has been the provision of a binding strip which is soft and flexible enough to provide comfort, yet tough enough to provide the desired protection against wear, and to hold its shape through long periods of time. In the present structure the outer portions of the spring loops 6 and 8 are enclosed in a four-layer thickness of paper, and are well shielded by said paper, and by cord 34. Said cord is disposed principally within the marginal limits of the spring assembly, and thereby derives reinforcement from both the paper layers and from the springs themselves. This arrangement provides a binding strip which holds its shape much better over long periods of time.

It will be noted in Fig. 2 that the binding strips are so positioned that the multiple-layer portion of the binding strips are disposed on the outer faces of the spring assembly, while the flaps 24 are disposed inside of the spring assembly. Thus the cushioning effect provided by layers 26 is extended inwardly a considerable distance from the edges of the assembly. Furthermore layers 26 impart a degree of stiffness to that portion of the binder lying against the outer surface of the spring assembly, whereby it resists deformation by the spring wires and maintains a substantially flat surface on which the mattress padding may rest. Flap 24, on the other hand, readily conforms to the wires since it is relatively thin and flexible. Making said flap of crepe paper assists in this matter since the crinkles in such paper render it more easily deformable.

Although I have shown a specific embodiment of my invention, it is readily apparent that many minor changes of construction could be made without departing from the spirit of the invention.

What I claim as new and desire to protect by Letters Patent is:

1. A binding strip for spring mattress structures comprising an elongated strip of flexible sheet material, an elongated cushioning member attached to one side of said strip, being longitudinally coextensive with said strip and disposed at one side of the longitudinal midline thereof, said strip being adapted to be folded longitudinally along its midline with said cushioning member on the outside to bring the transverse edge portions thereof into juxtaposition, and means for joining said edge portions together.

2. A binding strip for spring mattress structures comprising an elongated strip of pliable, easily deformable sheet material, a stiffening layer of pliable, compressible material secured to said strip, being longitudinally coextensive with said strip and extending transversely from one

edge thereof to a point on the opposite side of the midline thereof but spaced apart from the opposite edge thereof, a cord of cushioning material secured to said strip, being longitudinally coextensive with said strip and disposed at the side of the longitudinal midline thereof adjacent the stiffened edge thereof, said binding strip being adapted to be folded longitudinally along its midline with said cushioning cord on the outside to bring the transverse edge portions thereof into juxtaposition, and an adhesive coating on the surface of said binding strip inside of said fold.

3. A binding strip for spring mattress structures comprising an elongated strip of crepe paper, a stiffening layer comprising a plurality of layers of waffle paper secured to said crepe paper strip, being longitudinally coextensive with said strip and extending transversely from one edge of said strip a distance slightly greater than one-half the width of said strip, a cord like member of cushioning material secured longitudinally to one side of said strip and disposed at the side of the midline thereof adjacent the stiffened edge thereof, said binding strip being adapted to be folded longitudinally along its midline with said cushioning cord on the outside to bring the transverse edge portions thereof into juxtaposition, and a coating of adhesive on the surface of said binding strip inside of said fold.

30 4. A binding strip for spring mattress structures comprising a cover formed of an elongated strip of pliable material folded longitudinally to produce layers of unequal width, the layer of lesser width being greater than one-half the width of the layer of greater width, stiffening layers of pliable material disposed between said cover layers and coextensive with said layer of lesser width, said layer of greater width being offset outwardly to form a longitudinally extending loop disposed at the side of the midline of said binding strip adjacent the stiffened edge thereof, a cord-like member of stiffening material disposed in said loop, and a coating of adhesive over the surface of said binding strip opposite said cushioning member.

5. A binding strip for spring mattress structures comprising a cover formed of an elongated strip of pliable material folded longitudinally to produce layers to unequal width, the layer of lesser width being greater than one-half the width of the layer of greater width, stiffening layers of pliable material disposed between said cover layers and coextensive with said layer of lesser width, said layer of greater width being offset outwardly to form a longitudinally extending loop disposed at the side of the midline of said binding strip adjacent the stiffened edge thereof, two lines of stitching through said binding strip respectively at opposite sides of said loop, 60 a cord-like member of stiffening material disposed in said loop, and a coating of adhesive material over the surface of said binding member opposite said cushioning member.
